[57] **CLAIM**

The ornamental design of a diamond-plated tip for an interdental restoration instrument, as shown and described.

DESCRIPTION

FIG. 1 is a frontal view of the diamond plated tip for the interdental restoration instrument;

FIG. 2 is a rear view of the diamond plated tip for the interdental restoration instrument;

FIG. 3 is a side view of the diamond-plated tip for the interdental restoration instrument, the opposite side thereof being identical;

FIG. 4 is a view from the back end of the diamond-plated tip for the interdental restoration instrument; and,

FIG. 5 is a view from the end opposite the end of FIG. 4.
